UNITED STATES PATENT OFFICE.

THOMAS H. DISERENS, OF DALLAS, TEXAS, ASSIGNOR OF ONE-HALF TO JAMES C. GARNER, OF BROWNSWOOD, TEXAS.

STREET-SWEEPING MACHINE.

1,071,301.

Specification of Letters Patent. Patented Aug. 26, 1913.

Application filed March 24, 1911. Serial No. 616,630.

To all whom it may concern:

Be it known that I, THOMAS H. DISERENS, a citizen of the United States, residing at Dallas, in the county of Dallas and State of Texas, have invented certain new and useful Improvements in Street-Sweeping Machines, of which the following is a specification.

This invention pertains to improvements in street sweeping machines.

The object of the invention is to provide what may be termed a "dustless street sweeping machine" and one which includes a combined vacuum and pressure mechanism acting in conjunction with conveyers whereby the sweepings are taken up and distributed in the following manner: the heavy particles being delivered to conveyers which carry the same to a closed receptacle, the lighter particles being carried to a separator where said particles are removed from the air current and delivered to one of the conveyers; the dust laden air current passing from the separator to a purifying tank and then through a drying drum from which the air current passes to the exhaust nozzle.

Further features reside in the provision of a revolving cylindrical brush; mechanism for adjusting the brush; mechanism for adjusting the frame of the machine; mechanism for preventing the air current passing from the separator to the conveyer with the lighter particles; a revolving gutter brush; a device for raising the gutter brush; and mechanism for conveying the sweepings of the gutter brush to the separator.

A still further object of the invention is to provide a device of this character that will be strong, durable, efficient and simple and comparatively inexpensive to construct; also one in which the several parts will not be likely to get out of working order.

With the above and other objects in view the invention has relation to certain novel features of construction and operation, an example of which is described in the following specification and illustrated in the accompanying drawings, wherein:

Figure 1 is a side elevation with certain parts illustrated in section, Fig. 2 is a plan view, certain parts being illustrated in section and other parts broken away to show under-lying constructions, Fig. 3 is a front elevation; Fig. 4 is a detail of the roller

driving gears, Fig. 5 is a detail of the driving mechanism between the bucket conveyer and the screw conveyer, Fig. 6 is a detail in section of the separator valve, Fig. 7 is a rear elevation of the machine, Fig. 8 is a detail in section taken on the line *s-s* of Fig. 7 and showing one of the trash box fastenings, Fig. 9 is a detail in section showing one of the other fastenings used with the trash box, and Fig. 10 is a section on the line *a-a* of Fig. 9.

In the drawings the numeral 1 designates a frame which is preferably formed of metal in angle-iron form. This frame has side beams 2 and 3 respectively, central beams 4, and cross beams 5, 6 and 7 respectively. At the forward end of the machine the side beams are bent inward and secured to the central beams. The frame is mounted on ground wheels 8 and 9 respectively. As the connection between the wheels 8 and the frame is the same on both sides, a description of one will suffice for both. The wheel 8 is mounted to revolve on an axle or trunnion 10 extending laterally outward from a vertical slide bar 11 having gear teeth on its rear edge. The forward edge of the slide bar engages in the channel of a keeper 12 secured to the adjacent side beam. This keeper holds the bar a short distance from the beam as is best shown in Fig. 2. A shaft 14 extends transversely over the frame and a gear 15 fixed on the end thereof meshes with the teeth of the slide bar. An arm 16 fixed on the shaft depends therefrom and has connection at its lower end with the rear end of a link 17 extending forward under the frame.

Near the forward end of the frame a rock shaft 19 is mounted thereon and has a depending arm 18 connected to the link 17. This shaft extends across the central bars 4 and a lever 20 is fixed on its end. This lever is provided with a plunger engaging a segmental rack 21. It is apparent that by the connections described the shaft 14 is rocked when the lever is swung. The rocking of the shaft 14 rotates the gears 15 which ride up and down on the slide bars thereby raising or lowering the rear portion of the frame.

The wheels 9 are set comparatively close together and are mounted on an inverted T-shaped support 22 which carries an annular

gear member 23 at its upper end. The gear member supports an annular plate 24 secured to the under sides of bars 4. In a bearing 25 secured on the side of a cross bar 26, a vertical steering post 27 is mounted. This post has a hand wheel 28 at its upper end and a pinion 29 at its lower end which meshes with the gear member 23. By this means the machine is guided from an operator's seat 30 suitably supported on the frame adjacent the wheel 28 and the lever 20.

Between the wheels 8 a cylindrical broom or brush 31 is located and extends transversely under the frame, the wheel supporting devices permitting the brush to project above the center of the wheels if necessary. A housing 32 incloses the brush except the lower portion thereof. The brush has trunnions 33 which extend through vertical slots 34 of the sides of the housing as shown in Fig. 7. Collars 35 are loosely confined on the trunnions and connected to the lower ends of chains 36 which are employed in raising or lowering the brush as the case may be. These chains depend from the free ends of levers 37 fixed on the ends of a horizontal rock shaft 38 suitably hung from the frame. An arm 39 extends upward from the said shaft and has connection with the rear end of a link 40 connected at its forward end to the upper end of an arm 41 fixed on the end of a rock shaft 42 supported in the bars 4. At its opposite end the shaft 42 supports a lever 43 provided with a locking plunger engaging a segmental rack 44 secured to one of the bars 4 as shown in Fig. 2. This lever when swung raises and lowers the brush by means of the connections described.

Along the front side of the housing a horizontal trough 45 is provided and closed at its ends by the sides of the housing. In this trough a screw conveyer 46 is mounted. The heavy particles swept up by the brush fall into the trough and are carried by the conveyer to the right hand end with relation to Fig. 3. Near that end the trough is cut out and the conveyer terminated to permit the passage of the buckets of an elevator 47 as shown in Fig. 1. The heavy particles are removed from the trough and carried upward by the elevator which is secured to the inner side of the beam 2.

The elevator at its upper end has a laterally directed discharge spout extending down to the forward end of a longitudinal trough 48 supported over the beam. A screw conveyer 49 is mounted in this trough and conveys the particles discharged by the elevator, rearward to a trash box 50 hung from the frame. A screw conveyer 51 extends across the box from the rear end of the conveyer 49 and at right angles thereto as shown in Fig. 6. A hood is placed over the

conveyer 51 and forms part of a covering secured over the box. The conveyer 51 acts to distribute the particles across the box.

The box is arranged to be removed when filled. The cover 52 extends over each side of the box and projects under the cross bars 7. To these projecting portions of the cover and on their under sides, angle members 53 and 54 are secured as shown in Figs. 8 and 9. A plurality of pairs of ears 55 depend from the member 53. Between each pair of ears an eye bolt 56 is pivoted and arranged to swing upward through a slot cut in the member 53, cover 52 and member 7. The free end of each bolt is threaded and each bolt receives a wing nut 57 which is screwed down on the member 7 and the box is thus fastened in place, as shown in Fig. 8.

A plurality of inverted bolts 58 are each shouldered and fastened in the member 54 as shown in Fig. 9. Each bolt receives a wing nut 59 which is screwed down on the bar 7 to fasten the box in place. At each bolt 58 the bar 7 is cut out at 60 which provides a passage for the bolt and wing nut when the box is moved rearwardly (see Fig. 10).

Near the center of the frame a rotary fan 61 is suitably supported. From one side of the center of this fan a suction pipe 62 depends and is gradually merged into a nozzle 63 flared laterally but contracted transversely toward its lower end. This inlet nozzle 63 extends transversely of the machine over the screw conveyer 46. Between the said conveyer and the inlet end of the nozzle a pair of horizontal corrugated or spiked rollers 64 are mounted in opposed relation and so as to obstruct a portion of said inlet end. These rollers are revolved so as to tear up paper and the like and throw it into the nozzle and prevent trash from obstructing the entrance to the nozzle.

It is apparent that lighter particles which do not fall into the conveyer trough 45 will be drawn into the nozzle 63 by the suction of the fan 61. The particles drawn into the fan are ejected through a tangential flue 65 which extends from the top of the fan casting. This flue is horizontal and projects forward and to one side so as to discharge into the upper cylindrical end 66 of a conical separator 67 and to occupy a tangential relation to the same. The particles are carried around the separator which owing to its conical shape and the whirling action of the air current deprives said current of the heavier of said particles which fall into a rotary valve 68 at the lower end of the separator as shown in Fig. 6. This valve acts to deposit the particles in a discharge tube 69, but prevents the escape of the air current therethrough. The tube 69 empties into the elevator 47 as shown in Fig. 1.

From the center of the separator a flue 70

extends upward. The lower end of the flue 70 projects only a short distance into the conical portion 67 and after emerging from the separator said flue is arched and projects toward the center of the frame and at an angle forward, its forward end entering one side of the dome of a purifying tank 71. The air current passing out through the flue 70 carries substantially nothing but fine dust. The flue 70 extends to the center of the tank and projects downward, but terminates a short distance above the bottom of the tank. In the lower portion of the tank, a plurality of horizontal partitions 72 are supported and the two uppermost partitions surround the flue, while the others are below the end of the said flue and have central openings 73 directly under the discharge end of the flue as shown in Fig. 1. Water or other liquid is placed in the tank so as to cover all the partitions below the discharge end of the flue. All of the partitions are perforated. It is to be understood that the dust laden air current will be ejected from the flue 70 under considerable pressure and the openings 73 provide an unobstructed passage to the bottom of the tank except the obstruction offered by the water. The pressure will force the water upward in the tank through the perforations of the partitions which serve to divide the water into a plurality of fine jets. It is obvious that the water will remove the dust from the air current and this dust will deposit on the bottom of the tank in the form of mud. At one side of the tank a clean-cut opening and cover 74 is provided through which the mud may be removed, however, I wish to state that the air current will convey very little dust to the tank as most of it will settle in the separator.

At the center of the dome of the tank 71 a flue 75 is secured. This flue is arched and extends downward and slightly rearward to the top of a drying drum 76. This drum is similar in shape to the separator and is located on the opposite side of the frame. The flue extends from the drum in substantially tangential relation thereto and acts to conduct the air current from the tank and also any water which may be forced out of the tank by the pressure of the said current. Such water upon entering the drum 76 would fall to the bottom of the same. A pipe 77 running from the bottom of the drum to the bottom of the tank maintains the water at the same level in both.

An exhaust flue 78 extends from a point below the cylindrical portion of the drum, up through the top of the drum and rearwardly to the center of the frame at a point in rear of the fan. At this point the exhaust flue is curved downward and is merged into an exhaust nozzle 79. The air current

whirling around the drum is deprived of all moisture and passes out through the flue 78 to the exhaust nozzle. The exhaust nozzle is flared laterally and contracted transversely toward its lower end. This nozzle has its lower portion at the rear of the housing 32 and curved slightly forward so as to discharge under the brush 31. The current of air thus discharged will assist the brush in the sweeping operation and delivering the "sweepings" to the trough 45 and nozzle 63.

For the purpose of sweeping gutters and in close proximity to curbing I provide an auxiliary sweeper. This sweeper comprises a comparatively short cylindrical brush or broom 80 which is suspended from the frame in front of the inlet nozzle 63 and on the side opposite to the elevator. The brush is fixed on the end of a shaft 81 mounted to revolve in bearings at the lower ends of hangers 82 which are pivoted at their upper ends to bearing boxes 83 secured to the beam 3 and the adjacent center beam 4 respectively. These bearing boxes support a horizontal counter shaft 84 under the frame. The hangers support the shaft 81, permitting it to be swung upward and also space it from the counter shaft.

For raising and lowering the brush 80 a bell-crank lever 85, shown in Figs. 1, 2 and 3, is supported on the inner side of the beam 3 and has a link 86 depending from its horizontal member which is pivoted at its lower end to one of the hangers. From the vertical member of the lever a rod 87 extends forward over the frame to an arm 88 mounted on a rock shaft 89 supported on the frame as shown in Figs. 2 and 3. On the opposite end of the rock shaft a hand lever 90 is secured and swings against a segmental rack 91, a plunger being provided on the lever and engaging with the rack to lock the parts in position. By means of the hand lever the shaft 89 may be rocked and the brush raised or lowered.

For removing the "sweepings" and dust from in front of the brush 80, a curved suction nozzle 92 is disposed in front of the brush and supported by an arm 93 projecting from the adjacent hanger as shown in Fig. 3. The nozzle is contracted at its upper end and has connection with the lower end of a flexible pipe 94 which is connected at its upper end with a longitudinal pipe 95 mounted under the beam 3. This pipe 95 extends rearwardly and is joined to another pipe 96 which extends upward and across the frame in front of the suction pipe 62 into which said pipe 96 is turned. The matter entering the suction nozzle 92 is drawn into the suction pipe 62 and the fan 61. It will be noted that the brush 80 extends laterally beyond the adjacent ground wheel 8 and there are no projections to pre-

vent it from operating close to a curbing. It also overlaps the brush 31 and may be raised when not in use.

For driving the machine and the various parts, a proper engine (not shown) is suitably supported on the frame in position to have connection with a gear or sprocket 97 fixed on a transverse drive shaft 98 supported under the frame between the separator 10 and the purifying tank. This shaft extends on each side of the frame and has sprockets 99 fixed on its ends. Sprocket chains 100 pass about these sprockets and larger sprockets 101 secured to the ground wheels 8, thus driving the machine forward.

15 A bearing bracket 102 depends from the outer side of the beam 2 and carries a gear 104 which meshes with a gear 103 secured on the drive shaft adjacent the sprocket 99. The gear 104 is fixed on the hub of a sprocket 105, the gears reversing the direction of rotation. This sprocket 105 receives a sprocket chain 106 which passes about a sprocket 107 mounted on one of the 20 trunnions 33 of the brush 31 which is thus revolved in a direction opposite to that of the ground wheels, but driven from one end only.

25 A sprocket 108 (Fig. 3) is secured on the drive shaft near the elevator and drives by means of a chain 109 a sprocket 110 secured on the upper shaft 111 of the elevator 47. The lower shaft 112 of the elevator is extended outwardly (Figs. 3 and 5) and has fixed thereon a gear 114 which meshes with a gear 115 secured on the extended end of the shaft of the screw conveyer 46. At its opposite end the said conveyer shaft is extended and has fixed thereon a sprocket 116 (Fig. 4) which drives by means of a chain 117 a sprocket 118 fixed on the end of one of the rollers 64 and adjacent a pinion 119 (Fig. 7) which meshes with a pinion 120 fixed on the end of the other roller, said rollers thus being revolved in opposite directions.

30 On the upper elevator shaft a second sprocket 121 is fastened (Figs. 2 and 3) and drives by means of a chain 122, a sprocket 123 connected to a bevel gear 124 meshing with a bevel gear 125 secured on the forward projecting end of the shaft of the screw conveyer 49 whereby motion is imparted to the latter. On the rear end of the conveyer shaft a bevel gear 126 is secured and meshes with a similar gear 127. A spur gear 128 is fastened on the side of the gear 127 and meshes with a similar gear 129 fixed on the extended end of the shaft 120 of the conveyer 51.

35 For driving the valve 68 under the separator, a sprocket 130 is secured on the drive shaft 98 and drives by means of a chain 131 a sprocket 132 mounted on a shaft 133 suitably supported adjacent the said valve. On

its opposite end the shaft has a worm 134 which meshes with a worm gear 135 secured to the shaft of the valve.

40 For operating the fan 61, a sprocket 136 is fastened on the drive shaft 98 and drives by means of a chain 137, a sprocket 138 fixed on a counter shaft 139 suitably supported transversely of the frame under the drum 76 (Fig. 2). On this counter shaft a pulley 140 is fastened and drives by means of a belt 75 141 a pulley 142 secured on the projecting end of the shaft of the fan.

45 For driving the auxiliary brush 80 a sprocket 143 is fixed on the drive shaft 98 and drives by means of a chain 144 a sprocket 145 mounted on a counter shaft 146 (Fig. 2) which also carries a gear 147. This counter shaft 146 is supported by the bar 5. The gear 147 meshes with a gear 148 fixed on the counter shaft 84 and reverses 50 the direction of motion. Midway between the hangers 82 a sprocket 149 is fixed on the counter shaft 84 and drives by means of a chain 150 a sprocket 151 secured on the brush shaft 81.

55 What I claim is:

1. In a street sweeping machine, a rotary brush, a horizontal trough supported in front of the brush longitudinally thereof, a housing inclosing the brush and connected to one edge of the trough, a screw conveyer mounted in the trough longitudinally thereof, and a suction nozzle having its entrance over the conveyer and extending substantially the entire length of said conveyer.

upper central portion of the nozzle, a suction fan having connection with the pipe, and a pair of roughened rollers interposed between the lower end of the nozzle and the 5 screw conveyer and disposed longitudinally of the screw conveyer and the nozzle.

5 In a street sweeping machine, a frame, a rotary brush, a trough arranged in front of and longitudinally of the brush, a housing inclosing the brush and to which the trough is attached, a screw conveyer mounted in the trough, a suction nozzle over the conveyer having its entrance longitudinally of the conveyer, a suction pipe extending 10 from the nozzle, a suction fan on the frame to which the pipe is connected, a separator mounted on the frame and having pipe connection with the fan, an air discharge nozzle 15

mounted directly in rear of the brush, and an air discharge pipe leading from the separator to the discharge nozzle. 20

6. In a street sweeper, the combination with a rotary brush, and a suction nozzle, of a pair of rollers disposed longitudinally on each side of the entrance end of the 25 nozzle and provided with a plurality of peripheral projections, and means for revolving said rollers in opposite directions.

In testimony whereof I have signed my name to this specification in the presence of 30 two subscribing witnesses.

THOMAS H. DISERENS.
